US00D945973S

(12) **United States Design Patent** (10) **Patent No.:** **US D945,973 S**
Emigh (45) **Date of Patent:** **** Mar. 15, 2022**

(54) **TOUCH CONTROL PANEL WITH
MOVEABLE SHUTTER**

(71) Applicant: **Brilliant Home Technology, Inc.**, San Mateo, CA (US)

(72) Inventor: **Aaron T. Emigh**, Incline Village, NV (US)

(73) Assignee: **Brilliant Home Technology, Inc.**, San Mateo, CA (US)

(**) Term: **15 Years**

(21) Appl. No.: **29/704,423**

(22) Filed: **Sep. 4, 2019**

(51) LOC (13) Cl. **13-03**

(52) U.S. Cl.

USPC **D13/162**

(58) **Field of Classification Search**

USPC D13/162, 164, 184, 199, 170; D14/371, D14/381, 382, 388, 389

(57) **CLAIM**

The ornamental design for a touch control panel with moveable shutter, as shown and described.

DESCRIPTION

FIG. 1 is a front isometric view of a touch control panel with moveable shutter for a sensor area, the moveable shutter being in a closed position, under a first embodiment.

FIG. 2 is a frontal view of FIG. 1.

FIG. 3 is a front isometric view of the touch control panel with moveable shutter in an open position, under the first embodiment.

FIG. 4 is a frontal view of FIG. 3.

FIG. 5 is a front isometric view of a touch control panel with moveable shutter for a sensor area, the moveable shutter being in a closed position, under a second embodiment.

FIG. 6 is a frontal view of FIG. 5.

FIG. 7 is a front isometric view of the touch control panel with moveable shutter in an open position, under the second embodiment; and,

FIG. 8 is a frontal view of FIG. 7.

1 Claim, 8 Drawing Sheets
